[57] **CLAIM**

The ornamental design for a display module for audio/video cassettes and the like, as shown and described.

DESCRIPTION

FIG. 1 is a perspective view of a display module for audio/video cassettes and the like showing my new design;

FIG. 2 is a front elevational view thereof;

FIG. 3 is a rear elevational view thereof;

FIG. 4 is a side elevational view the opposite side being identical thereto;

FIG. 5 is a top plan view thereof;

FIG. 6 is a bottom plan view thereof;

FIG. 7 is a perspective view of a second embodiment of the display module for audio/video cassettes and the like shown in FIG. 1, the top and bottom views being identical to FIGS. 5 and 6 respectively;

FIG. 8 is a front elevational view, the rear being identical thereto;

FIG. 9 is a side elevational view, the opposite side being a mirror image thereto;

FIG. 10 is a perspective view of a third embodiment of the display module for audio/video cassettes and the like shown in FIG. 1; the opposite side being a mirror image thereof; the top and bottom views being identical to FIGS. 5 and 6 respectively;

FIG. 11 is a front elevational view thereof;

FIG. 12 is a rear elevational view thereof; and

FIG. 13 is a perspective view of the display module for audio/video cassettes and the like shown within a display module system, in a stacked position, shown in phantom, to illustrate an embodiment within which the display module for audio/video cassettes and the like can be used.
